UNITED STATES PATENT OFFICE.

FREEMAN A. TABER, OF BOSTON, MASSACHUSETTS.

IMPROVEMENT IN LAMP-BURNERS.

Specification forming part of Letters Patent No. **171,638**, dated December 28, 1875; application filed August 9, 1875.

To all whom it may concern:

Be it known that I, FREEMAN A. TABER, of Boston, Suffolk county, Massachusetts, have invented certain Improvements in Lamp-Burners, of which the following is a specification:

The drawing accompanying this specification represents a vertical section of a lamp-burner containing my improvements.

In this drawing the base of the burner, which screws into the mouth of the lamp, is shown at A, and the wick-tube, which is secured to such base, is shown at B, the star-wheel for elevating the wick being shown at C. The chimney-rest, which is supported in part by the upper portion of the wick-tube, and in part by the base A, is composed of an inner vertical tube or sleeve F, joined at or near its bottom to a horizontal perforated shell, a, which terminates in an upright annular wall, G, while the conical air-deflector, which surrounds the upper portion of the sleeve F, and finds a support within the wall G, is shown at H.

The above description embraces the construction of lamp-burners now generally in use. In carrying out my invention, the purpose of which is, mainly, to enable heavy hydrocarbon oils to be burned without smoke with a single wick-tube, I extend the sides of the sleeve or tube F a short distance above the top of the wick-tube, leaving notches or depressions c c at each end, to permit of expansion or spreading of the flame. I then pierce the lower end of the sleeve F with a series of air-inlet ports, d d, &c., to permit of ingress of oxygen to aid in supporting perfect combustion of the oil at the top of the wick-tube.

I have found in practical use of a burner constructed as explained—that is, with the sleeve F extending above the wick-tube, and in connection therewith the employment of the air-inlets d—that I obtain the following results: First, incrustation of the top of the wick is very greatly retarded—a matter which has been very difficult to accomplish in the burning of heavy hydrocarbon oils, a product of petroleum now extensively in use; second, by inclosing two wicks side by side (or a single wick folded) in the wick-tube, which I operate together by the wheel C, I obtain the same effect as is produced by the employment of two wicks in separate tubes placed immediately contiguous to each other, thus avoiding duplex gearing, and liability to disarrangement consequent upon the use of two tubes.

I claim—

1. In a lamp-burner, the combination, with a slotted deflector and a flat wick-tube, of a sleeve whose sides extend a short distance above the wick-tube, and whose ends at the top are notched to permit expansion or spread of the flame, substantially as set forth.

2. The sleeve F, provided with air-admitting perforations, and having its sides extended a short distance above the wick-tube, in combination with the flat wick-tube and slotted deflector of a lamp-burner, substantially as set forth.

FREEMAN A. TABER.
